FOREIGN PATENT DOCUMENTS

JP 1530257 8/2015

Primary Examiner — Samantha Q Lawrence(74) *Attorney, Agent, or Firm* — 3M Innovative Properties Company; Trisha D. Adamson(57) **CLAIM**

The ornamental design for a liquid applicator, as shown and described.

DESCRIPTION

FIG. 1 is a front perspective view of a liquid applicator, showing the new design;

FIG. 2 is a left side elevational view thereof, the right side elevational view being a mirror image of the left side elevational view;

FIG. 3 is a top perspective view thereof;

FIG. 4 is a bottom perspective view thereof;

FIG. 5 is top perspective view thereof; and,

FIG. 6 is a bottom perspective view thereof.

The solid line showing illustrates the claimed features within the design for the claimed article of manufacture, while the broken line showing illustrates the non-claimed features within the design for the claimed article of manufacture. The shading is provided to illustrate contour only and is not an indication of texture, gloss, etc.

1 Claim, 5 Drawing Sheets(56)
